FIG. 1

FIG. 2

FIG. 3

INVENTOR
ROY S. SANFORD
BY
R. W. McConkey
ATTORNEY

UNITED STATES PATENT OFFICE

ROY S. SANFORD, OF SOUTH BEND, INDIANA, ASSIGNOR TO BENDIX BRAKE COMPANY,
OF CHICAGO, ILLINOIS. A CORPORATION OF ILLINOIS

BRAKE

Application filed August 25, 1926. Serial No. 131,350.

This invention relates to brakes, and is illustrated as embodied in an internal expanding automobile brake. An object of the invention is to lessen the friction loss in the 5 brake-applying means, for example by providing novel rollers which are preferably adjustable to take up for the wear of the brake.

In one desirable arrangement the rollers 10 are mounted on the ends of the brake shoes, or equivalent friction means, by novel means providing for shifting them bodily to give the desired adjustment, for example by mounting them on angularly-adjustable 15 levers pivoted on the shoes. Various features of novelty relate to the mounting and adjustment of these levers.

The above and other objects and features of the invention, including various novel 20 combinations of parts and desirable particular constructions, will be apparent from the following description of one illustrative embodiment shown in the accompanying drawings, in which:

25 Figure 1 is a vertical section through the brake just inside the head of the brake drum, showing the shoes in side elevation;

Figure 2 is a partial section through the 30 end of one shoe, on the line 2--2 of Figure 1, showing the roller and lever in plan; and

Figure 3 is a partial section through the 35 adjusting means for one of the rollers.

The brake illustrated includes a rotatable drum 10, at the open side of which is a suitable support such as a backing plate 12. The friction device of the brake may include three 40 shoes 14, 16, and 18, shoe 14 being anchored on a pivot 20, shoe 16 being anchored on a pivot 22, and shoe 18 being connected to shoe 45 16 by a floating pivot 26. The brake is applied by forcing shoes 14 and 18 apart against the resistance of a return spring 28, shoe 16 being applied by shoe 18 against the resistance of an auxiliary return spring 30. The 50 idle position of shoe 16 may be determined by any suitable stop 32. Except as further described below, the above-listed parts or their equivalents may be of any desired construction, the present invention relating to 55 the means for applying the brake.

This brake-applying means is shown as including a novel thrust member such as a double cam 34 rocked by a suitable camshaft, and engaging rollers 36 and 38 rotatably mounted on the ends of shoes 14 and 18. The 55 cam 34 is shown with an end flange 40 engaging the ends of the rollers and confining the shoe ends against lateral movement.

Each of the rollers is rotatably mounted on a spindle 42 carried by the ends of a pair 60 of bellcrank levers 44 and 46 on opposite sides of the shoe end, the levers having an integral connecting part 48 passing through an opening 50 in the web of the shoe. Thus levers 44 and 46 and the connecting part 48 may be 65 regarded, if desired, as a single novel roller-carrying lever.

The levers are fulcrumed on pivots 52 carried by extensions of the shoe webs, with the roller-carrying arms extending radially of 70 the drum so that the rollers or other thrust members are in the angles between those web extensions and the ends of the shoes.

The web extensions of shoe 14 extends further inward radially of the drum, so that 75 roller 38 engages the cam 34 between the cam axis and the axis of drum 10, while roller 36 engages the cam between the cam axis and the outside of the drum. I prefer to form the cam 34 on its opposite sides with cylindrical surfaces or pockets 35 fitting over the rollers to determine the idle position of the cam, these cylindrical surfaces 37 merging into cam surfaces which wedge the rollers apart in applying the brake. Since the 80 roller 36 on the end of shoe 18 has approximately twice as far to go in applying the brake as has roller 38 on shoe 14, because of having to take up the clearance of the two 85 shoes 18 and 16, the distance radially of the 90 brake drum from the axis of cam 34 to the cylindrical surface embracing roller 36 is approximately double the distance from that axis to the cylindrical surface embracing 95 roller 38.

Adjustment of the levers is made by means such as stops or setscrews 54 threaded through the shoe webs inside of the openings 50, and engaging the connecting parts 48. The setscrews may if desired be provided 100

with locknuts 56. If preferred, ball spring locks 58 may be provided for the setscrews.

It will be seen that the setscrews 54 may be manipulated to rock the levers to shift rollers 36 and 38 toward and from the axis of cam 34, along arcs which are substantially perpendicular to the drum radii.

While one illustrative embodiment has been described in detail, it is not my intention to limit the scope of the invention to that particular embodiment, or otherwise than by the terms of the appended claims.

I claim:

1. A brake comprising, in combination, a drum, a friction device engageable with the drum, a brake-applying device adjacent the ends of the friction device, rollers carried by one of said devices and engaging the other, and a device carried entirely by each of said ends for bodily shifting the corresponding roller to adjust for wear of the friction device.

2. A brake comprising, in combination, a drum, a friction device engageable with the drum, a brake-applying device adjacent the ends of the friction device, rollers carried by the ends of the friction device and engaging the brake-applying device, and a device carried entirely by each of said ends for bodily shifting the corresponding roller to adjust for wear of the friction device.

3. A brake shoe having, in combination, a lever pivoted at one end of the shoe, a thrust member on the lever, and means on the shoe for adjusting the lever angularly to shift said member lengthwise of the shoe to take up for wear.

4. A brake shoe having, in combination, a lever carrying at one end a thrust member and pivoted on the shoe between its ends, and means on the shoe engaging the other end of the lever to adjust it to shift the thrust member.

5. A brake shoe having, in combination, a lever carrying at one end a thrust member and pivoted on the shoe between its ends, and a stop carried by the shoe and engaged by the other end of the lever when thrust is applied to said member.

50 6. A brake shoe having a web formed with an opening, in combination with a thrust lever pivoted on the shoe and having a part in said opening, and a stop on the side of said opening and engaged by the lever when thrust is applied thereto.

7. A brake shoe having a web formed with an opening, in combination with a thrust lever pivoted on the shoe and having a part in said opening, and a setscrew threaded through part of the web at one side of said opening and engaged by the lever when thrust is applied thereto.

8. A brake shoe having a web with an opening, in combination with a pair of levers pivotally mounted on opposite sides of the

shoe and having at one end a connecting part passing through said opening.

9. A brake shoe having a web with an opening, in combination with a pair of levers pivotally mounted on opposite sides of the shoe and having at one end a connecting part passing through said opening, together with a thrust roller rotatably mounted between the unconnected ends of the levers.

70 10. A brake shoe having a web with an opening, in combination with a pair of levers pivotally mounted on opposite sides of the shoe and having at one end a connecting part passing through said opening, together with a limiting stop engaging said connecting part.

75 11. A brake shoe having a web with an opening, in combination with a pair of levers pivotally mounted on opposite sides of the shoe and having at one end a connecting part passing through said opening, together with a setscrew threaded through part of the web and engaging the connecting part.

80 12. A brake shoe having an extension at its inner edge at one end, in combination with a bellcrank lever pivoted on said extension and having one end extending substantially radially outward, and a thrust member carried by the lever in the angle between said extension and the end of the shoe, the other end of the bell crank lever extending along the side of the shoe and engaging a part carried by the shoe.

85 13. A brake comprising, in combination, a drum, a friction device having parts of different lengths and having a roller rotatably mounted at each end, and a cam having on its opposite sides cylindrical surfaces fitting against the rollers and determining the relative idle positions of the cam and the rollers and merging into cam surfaces wedging against the rollers when the cam is turned about its axis, the distance from said axis radially of the drum to the cylindrical surface fitting against the roller on the longer part of the friction device being greater than the distance from said axis to the cylindrical surface fitting against the roller on the shorter part of the friction device.

90 In testimony whereof, I have hereunto signed my name.

ROY S. SANFORD.
